CLAIM

The ornamental design for a security light mounting plate, as shown and described.

DESCRIPTION

FIG. 1 is an upper right perspective view of a security light mounting plate design with a mating uninstalled security light;

FIG. 2 is an upper left front perspective view of the security light mounting plate of FIG. 1;

FIG. 3 is a front view of the security light mounting plate design of FIG. 1;

FIG. 4 is a top view of the security light mounting plate design of FIG. 1;

FIG. 5 is a bottom view of the security light mounting plate design of FIG. 1;

FIG. 6 is a left side view of the security light mounting plate design of FIG. 1;

FIG. 7 is a right side view of the security light mounting plate design of FIG. 1;

FIG. 8 is an upper perspective view of the uncombined security light mounting plate design with an uninstalled security light of FIG. 1; and,

FIG. 9 is an upper perspective view of the combined security light mounting plate design with an installed security light of FIG. 1.

The broken lines showing portions of the security light mounting plate form no part of the claimed design. The broken lines in FIGS. 8 and 9 showing environmental subject matter of the security light form no part of the claimed design. The broken line arrows are included to illustrate the relationship between the security light and the mounting plate and form no part of the claimed design.
